FRED B. KING AND ROBERT L. STEVENS, OF ALBION, MICHIGAN, ASSIGNEES TO
NATIONAL SPRING & WIRE COMPANY, OF ALBION, MICHIGAN, A CORPORATION
OF MICHIGAN.

CUSHIONED SEAT.

1,419,270.

Specification of Letters Patent. Patented June 13, 1922.

Application filed December 17, 1914. Serial No. 877,714.

To all whom it may concern:

Be it known that we, FRED B. KING and ROBERT L. STEVENS, citizens of the United States of America, residing at Albion, in the 5 county of Calhoun and State of Michigan, have invented certain new and useful Improvements in Cushioned Seats, of which the following is a specification, reference being had therein to the accompanying drawings.

10 The invention relates to cushioned seats particularly designed for use in vehicles, and it is the primary object of the invention to obtain a construction in which the cushion and its skirt are so secured to the spring 15 frame as to be readily attachable thereto. To this end the invention comprises the construction as hereinafter set forth.

In the drawings:

Figure 1 is a cross section through a portion of the seat and spring frame showing our improvement applied thereto;

Figure 2 is an enlarged view of the lower edge of the skirt and metallic frame;

Figure 3 is a horizontal section there- 25 through;

Figure 4 is a section similar to Figure 2 showing the manner of engaging and disengaging the skirt;

Figure 5 is a perspective view of a modified construction;

Figure 6 is a section showing another modification; and Figure 7 is a perspective view of a portion of the strip attached to the skirt.

In the construction of seats for vehicles, 35 such for instance as used in automobiles, it is usual to form a padded cushion which is supported upon a spring frame, the sides of said frame being enclosed by a skirt depending from the cushion. The lower edge of this skirt is usually attached to the marginal bar 40 of the frame by looping around the same and stitching. Thus, whenever it is necessary to make any repairs necessitating the removal of the skirt the stitched seam must be ripped.

45 Furthermore the time required for thus attaching the skirt to the frame is considerable. With the present invention the construction is simplified and the time required for assembly reduced by substituting for the 50 stitched seam a series of clips, which are secured to the skirt and are quickly engageable with and disengageable from the spring frame.

As shown in Figures 1 and 2, A is the 55 cushion, B the skirt, C the springs and D the

lower frame to which the springs are secured and which has a marginal portion E. F are hooked clips, which are attached adjacent to the lower edge of the skirt and are adapted to be engaged with the marginal bar E of 60 the frame by first slightly compressing the springs C so as to relieve tension on the skirt, as shown in Figure 4. In the construction shown in Figure 6, the hooked clips F are directly attached to the skirt by suitable 65 means, such as the riveted fasteners G. We prefer, however, to provide the lower edge of the skirt with a metallic frame to which the clips are attached, and as shown in Figure 2, this frame is formed of a strip of 70 sheet metal H having a beaded lower edge I, which strip extends around the skirt on the inner face thereof. If desired the skirt may be detachably secured to the strip by buttons J having bendable brads K passing through 75 the fabric and apertures in the strip. The clips F are secured to the inner face of the strip H in any suitable way, but preferably by being formed of integral struck-out portions of said strip, as shown in Figure 7. 80

In the construction shown in Figure 5, instead of employing a sheet metal strip a wire L is stitched into a loop M at the lower edge of the skirt and the hooks F are welded or otherwise secured to this wire. This construction requires the stitching operation, but in common with the construction shown in the other figures is quickly attachable to or detachable from the spring supporting frame. 90

With all the various constructions shown and described, the cushion can at any time be quickly removed by placing the springs under slight compression and then successively disengaging the hooks F. This will 95 permit of replacing a broken spring or other repairs without injury to the skirt.

When the seat is in use the spring frame rests in the hooked clips and is supported upon the skirt frame, so that there is no tendency for the parts to disengage by the flexing of the springs. Also as the skirt frame is secured to the inner face of the skirt the attachment between the latter and the spring frame is concealed. 100

What we claim as our invention is:—

1. In a seat, the combination with a spring frame and a cushion, of a skirt depending from said cushion, enclosing said frame, a metallic strip secured to the inner face of 110

- said skirt adjacent to the lower edge thereof, and a plurality of inwardly-projecting upwardly-turned hooks on said strip for detachably engaging said spring frame.
- 5 2. In a seat, the combination with a spring frame and a cushion, of a skirt depending from said cushion, enclosing said frame, a metallic strip extending around the inner face of said skirt adjacent to the lower edge 10 thereof, a plurality of inwardly-extending upwardly-turned hooks on said strip for detachably engaging said spring frame, and quick attachment means between said strip and said skirt.
- 15 3. In a seat, the combination with a spring frame and a cushion, of a skirt depending from said cushion enclosing said frame, a sheet metal strip extending along the inner face of said skirt adjacent to the lower edge 20 thereof, said strip being provided with a beaded lower edge, and hooked clips struck inwardly from said strip for detachably engaging said spring frame.
4. An upholstered cover for spring or similar structures, comprising covering material 25 including a seat portion and side facings, a metallic frame to which the lower edges of the side facings of the covering material are secured, and means whereby the frame secured to the covering material may be sprung over the base of the spring or similar structure.
5. An upholstered cover for spring or similar structures comprising covering material 30 including a seat portion and side facings, a metallic frame to which the lower edges of
- the side facings of the covering material are secured, and means whereby the frame secured to the covering material may be sprung over the base of the spring or similar structure, said last mentioned means comprising integral struck-out portions of said frame.
6. In a seat the combination with a spring frame and a cushion provided with a depending skirt, of a skirt frame formed of a metallic bar having portions struck out from the web thereof to form upturned hooks for engaging with the base of the spring frame.
7. In a seat the combination with a spring frame and a cushion provided with a depending skirt, of a skirt frame formed of a metallic bar having a flange with portions struck out to form upturned hooks for engaging with the base of the spring frame.
8. The combination with springs and a supporting frame therefor, of an upholstery section adapted to be supported by the springs and having a skirt portion and a flat-sided bar secured to and carried by said skirt portion, the latter having hooks struck out therefrom to engage the spring supporting frame from below the same, said bar having a depending part extending below the base of said hooks.
- In testimony whereof we affix our signatures in presence of two witnesses.
